(57) **CLAIM**

The ornamental design for a computer case storage container with internal wall ribs, as shown and described.

DESCRIPTION

FIG. 1 is an isometric or perspective view of my design for a computer case storage container with internal wall ribs with an insert object such as a compact disk shown with broken lines.

FIG. 2 is an external front view of the design shown in FIG. 1 with an insert object shown with broken lines.

FIG. 3 is an external back or rear view of the design shown in FIG. 1.

FIG. 4 is an external top view of the design shown in FIG. 1.

FIG. 5 is an external bottom view of the design shown in FIG. 1.

FIG. 6 is an internal (inside) view of the right side of the design shown in FIG. 1.

FIG. 7 is an internal (inside) view of the left side of the design shown in FIG. 1; and,

FIG. 8 is a perspective view of the design shown in FIG. 1 for insertion into computer case shown with broken lines. The broken lines in the drawings represent environmental structure only and form no part of the claimed design.
